DESIGN FOR A HANDLE FOR SPOONS.

Design No. 13,860, dated April 17, 1883.

UNITED STATES PATENT OFFICE.

AUSTIN F. JACKSON, OF TAUNTON, MASSACHUSETTS, ASSIGNOR TO REED & BARTON, OF SAME PLACE.

DESIGN FOR A HANDLE FOR SPOONS.

SPECIFICATION forming part of Design No. 13,860, dated April 17, 1883.

Application filed February 17, 1883. Term of patent 7 years.

To all whom it may concern:

Be it known that I, AUSTIN F. JACKSON, a subject of the Queen of Great Britain, residing at Taunton, in the county of Bristol and State of Massachusetts, have invented and produced a new and original Design for a Handle for Spoons, &c., of which the following is a specification.

My invention is in the nature of a novel design for the handles of spoons, forks, &c., analogous articles.

Referring to the accompanying photographic illustration, in which Figure 1 represents the front view, and Fig. 2 the back, of my design as applied to a spoon, I make the handle in outline with a slender shank portion, *a*, an enlargement, *b*, a little above the middle of the length of the handle, a slight reduction above this in width, and then a curved divergent 26 taper to a wide end, which end terminates abruptly with a double "ogee" curve at *c*. At this end there is on the face of the handle a transverse band, with a flower above it in relief. Between this point and the enlargement *b* is 25 a background, with a floral design in relief

located near the said enlargement. The face of this enlargement is subdivided into two squares with symmetrical center decorations, while angular lines of marginal finish proceed from the enlargement in direction more or less 30 longitudinal to the handle.

Having thus described my invention, what I claim as new is—

1. A handle for a spoon or analogous article, having in outline a shank, *a*, enlargement *b*, a reduced width above, then widening with a divergent curve, and ending at *c* in an abrupt double ogee curve, substantially as shown. 35
2. A handle for a spoon or analogous article, having a shank, *a*, an ornamented enlargement, *b*, a double ogee end, *c*, with a band and flower in relief, and between this and the enlargement a background with a contrasting decoration, substantially as shown and described. 40

AUSTIN FREDERICK JACKSON.
